US00D977247S

(12) United States Design Patent (10) Patent No.: US D977,247 S
(45) Date of Patent: * Feb. 7, 2023

(54) STORAGE BOX

(71) Applicant: Weijia Zhu, Shantou (CN)
(72) Inventor: Weijia Zhu, Shantou (CN)
() Term: 15 Years
(21) Appl. No.: 29/834,180
(22) Filed: Apr. 11, 2022
(51) LOC (14) Cl. 03-01
(52) U.S. Cl. USPC D3/270
(58) Field of Classification Search

(57) CLAIM

The ornamental design for a storage box, as shown and described.

DESCRIPTION

FIG. 1 is a first perspective view of a storage box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the figures and the areas within the broken lines show portions of the storage box that form no part of the claimed design.

1 Claim, 8 Drawing Sheets
